UNITED STATES PATENT OFFICE.

HERMAN A. POPPENHUSEN, OF HAMMOND, INDIANA, ASSIGNOR TO GREEN ENGINEERING COMPANY, OF EAST CHICAGO, INDIANA, A CORPORATION OF ILLINOIS.

FURNACE.

1,243,868.

Specification of Letters Patent. Patented Oct. 23, 1917.

Application filed December 6, 1916. Serial No. 135,467.

To all whom it may concern:

Be it known that I, HERMAN A. POPPENHUSEN, a citizen of the United States, residing at Hammond, in the county of Lake 5 and State of Indiana, have invented new and useful Improvements in Furnaces, of which the following is a specification.

This invention relates to improvements in furnaces, and more particularly to furnaces 10 of the mechanical stoker type, equipped with a movable form of grate, preferably of the traveling chain construction.

A desirable feature of construction in a furnace of the character described is the 15 provision of mechanical or forced draft, preferably delivered to the furnace through air ducts, which communicate with an air space or compartment below the active grate area. In furnaces so equipped the compartments are preferably formed by providing 20 a partition member or deflecting plate beneath the grate and serving to inclose the intermediate space from the entrance of free air from the lower portion of the furnace, the air from the forced draft ducts 25 being preferably conducted to the compartment through vertical passages at either side of the grate and formed between the side walls of the furnace and vertical partition 30 walls spaced inwardly from said side walls and extending from the floor of the furnace upwardly and in contact with the side margins of the deflecting partition plate, said vertical passages communicating with the 35 forced draft ducts located below the floor level of the furnace, through openings at the lower ends of said passages.

In addition to providing for the passage 40 of air to the grate, it is desirable to employ means for collecting and disposing of the small particles of unburned coal or ash, called "droppage" for convenience, which ordinarily falls through the interstices of the grate. Where a fine grade of coal is 45 burned, the quantity of droppage is considerable and would ordinarily be lost or inaccessible for reclaiming, and especially so in the particular construction employed, which would permit the droppage to ac- 50 cumulate in the air passages and forced draft ducts and eventually clog them up, inasmuch as these parts of the furnace are quite inaccessible for cleaning.

The purpose of this invention is to pro-

vide an arrangement of movable members 5 serving in two capacities, namely, as dampers for the purpose of changing from natural to forced draft, if occasion demands, and as swinging deflecting plates, adapted in one position to coöperate with the fixed 60 deflecting plate to form a trough or receptacle for the collection of the droppage, and adapted to be moved to permit the droppage to fall and to be deflected upon the furnace floor, and simultaneously covering the openings of the forced draft ducts. 65

Inasmuch as these plates are capable of performing either function irrespective of the other, the present invention pertains to the construction and operation of these members, as confined to the collection and disposal of the droppage in a furnace, a desirable arrangement being illustrated in the accompanying drawings, wherein—

Figure 1 is a view in longitudinal section 75 through a furnace containing the features of the invention;

Fig. 2 is a transverse section of the furnace, taken on line 2—2 of Fig. 1; and

Fig. 3 is a plan section taken on line 3—3 80 of Fig. 1, showing the arrangement of ducts and damper operating mechanisms.

Referring to the drawings, the parts of the furnace illustrated comprise, in general, the side walls 10, 10, of the brick construction common to furnace settings; a front wall 12; a coking breast 13, extending rearwardly and over the forward end of the fire box or combustion chamber, said front wall and coking breast supporting the front 85 header and forward end of the lower bank of boiler tubes 14. Rearwardly of the front wall 12, and extending upwardly from the floor of the furnace setting, is a bridge wall 15. Within the fire box and extending forwardly from the bridge wall 15 and beyond the front wall 12, is the grate 16, the same 90 having the form of an endless chain, as before mentioned, formed of a multitude of connected together links, the portion of the 100 upper horizontal grate extending rearwardly from the front wall forming the active or fuel bed supporting area of the grate.

The chain grate is supported and operated in the following manner: At the sides of the grate and in contact with the inner surface of the side walls 10, 10 are vertical side frame members 17, 17, provided along

their upper margins with a plurality of inwardly projecting flanges 18, 18. Spaced apart at suitable intervals along the flanges 18, 18 and preferably integral therewith, 5 are journal bearings 19 supporting the end journals of a plurality of parallel and transversely extending rollers 20, which pass beneath the upper portion of the chain grate and support the same. At the rear ends of 10 the side frame members 17, 17 are mounted plates or extensions 21, 21, which support journal bearings 22. A shaft 23 is journaled in said bearings 22, there being fixed upon said shaft a series of sprocket wheels 24, 24, 15 carrying the chain grate.

From the forward end of the furnace extend vertical side plates 25, 25, in the nature of exterior continuations of the side frame members 17. Journalized in suitable bearings 20 in said plates 25, 25 and extending between the same, is a shaft 26, likewise carrying a series of sprocket wheels 27 meshing with and carrying the forward end of the chain grate. Suitable driving mechanism (not shown) serves to rotate the sprocket shaft, thus moving the chain grate to carry the fuel rearwardly upon the surface of the grate. Immediately above the forward end of the grate 16 is the fuel hopper 28, comprising end walls, integral with the side plates 25, 25, and a downwardly inclined rear wall 29, said hopper communicating at its bottom with the fire box, through an elongated opening intermediate the lower edge of the front wall 12 and the surface of the grate 16, said opening being capable of regulation, as to size, by means of a vertically movable gate 30 and suitable actuating devices (not shown). The fuel is introduced onto the forward end of the grate, and is carried rearwardly on the moving grate until it reaches the rear end, in the form of ash, where it drops by gravity into the ash pit or other receptacle.

45 Referring now to the construction and arrangement of the interior of the furnace, the space below the upper chain or lead of the grate and inwardly from the front wall 12 of the furnace is preferably divided into 50 a plurality of chambers or compartments 31, 32, and 33, formed in the following manner: As shown in Figs. 1 and 3, the side frame members 17 consist of a plurality of sections, of equal length and arranged in pairs, 55 each pair forming the sides of the three compartments. Each section or side frame member is provided at its ends with vertical flanges 34, 34, arranged at right angles and extending inwardly in close proximity to the 60 lateral edges of the grate, there being preferably provided spaces between the flanges, extending the full height of the sections.

Extending transversely of the side frame members 17, 17 are a plurality of transverse frame members 35, the same having the

form of I-beam sections, that is, a vertical central web provided with transverse webs 36 and 37 along its upper and lower margins. The transverse frame members 35 are so positioned and of such widths as to extend vertically from the supporting rollers 19 downwardly in close proximity to the upper surface of the lower chain or lead of the grate. The ends of the side frame members extend into the spaces between the flanges 34 of the side frame members (the end portions of the webs 36 and 37 being removed through the portions between said flanges), and are secured to the side frame members by means of bolts 38 extending through the flanges 34.

Rigidly secured to and extending longitudinally between the transverse frame members 35 and spaced below the upper lead of the grate 16, are a plurality of deflecting plates 40, each plate being of an inverted V shape in cross-sectional contour, the inclined surfaces sloping downwardly from the central portion of the grate, and terminating in the vertical plane of the side margins of the grate and immediately above the edges of the lower lead thereof, there being a space separating the lower margins of the deflecting plate and the side frame members 17. The deflecting plates 40 form the bottom walls of the compartments, and, by reason of the oppositely sloping surfaces thereof, serve to divide the droppage falling upon the plates into two parts, which are carried by gravity downwardly toward the edges of the plate, as will hereinafter be more fully described.

Below the lower lead of the grate is provided a plurality of transverse plates 41 extending between the side frame members 17 and in the plane of the transverse frame members 35, the ends of said plates extending into the spaces between the flanges 34 of the side frame members 17 and connected thereto in the same manner as said transverse frame members. The upper margin of each plate 41 is spaced below the under surface of the grate, there being mounted in said space a series of rollers 42, which engage and support the lower portion of the grate, said rollers being provided at their ends with journals, which are mounted within bearings 43, 43, preferably formed integral with the plates 41 and located along the upper margins thereof and immediately below the lateral margins of the grate. The lower margins of the plates 41 are spaced above the floor level or bottom surface of the space below the grate, as shown in the drawings, thereby forming an opening 125 through each of the partition walls of the compartments, to the end that said compartments communicate with each other at their lower portions and adjacent to the floor of the furnace.

Associated with each compartment and cooperating with the deflecting plate 40 of each compartment, are two movable deflecting plates 44, 44, located at either side of the lower lead of the grate and extending upwardly from the floor of the furnace in the plane of the side margins of the grate and spaced inwardly from the side frame members 17.

10 Each of the deflecting plates comprises two hinged together plates 45 and 46 extending lengthwise of the compartment, the lower plate 46 being comparatively narrow in width and rotatively supported along its lower margin by a suitable hinge joint, preferably consisting of a downwardly facing groove formed in the lower edge of the plate 46 and engaging a rib 47 extending upwardly from the floor of the furnace. 15 The upper plate 45 is connected to the lower plate 46 by means of suitable hinges 48, so arranged as to permit the plates to be flexed in an outward direction. In normal position the two plates or parts 45 and 46 extend vertically in alignment with each other, the upper plate extending above the side margins of the deflecting plate 40 and having contact therewith, thereby forming with the inclined surfaces of the fixed plate 40, 20 two longitudinally extending troughs or receptacles, substantially V-shaped in cross-section.

As has been heretofore suggested, the deflecting plates 44 may also be utilized as 25 dampers to control the passage of free air to the several compartments, but inasmuch as this feature of the construction is fully described elsewhere, this feature is omitted from the present discussion, except as regards the vertical air passages, which are 30 formed when the deflecting plates are in the normal vertical position, as shown in full lines in Fig. 2. The vertical passages referred to are the spaces included between 35 the plates 44 and the side frame members, said passages or spaces being arranged in pairs 49, 49; 50, 50, and 51, 51, associated with the compartments 31, 32, and 33, and extend from the floor of the furnace, on opposite sides of the grate, and communicate 40 at their upper ends with their respective compartments. The passages are also closed from communication with the free air space below the grate by the deflecting plates 45 when in normal or vertical position.

The vertical passages communicate with a series of forced draft ducts, which are arranged as follows: Below the floor level of the furnace is provided a space extending 45 throughout the length and width of the grate and forwardly a short distance beyond the front wall of the furnace, said space being preferably separated from the space immediately below the grate by 50 means of a floor plate 52 of metal or other

suitable construction, but communicating with the lower ends of the vertical passages 49, 50, and 51 by means of a plurality of openings 53 in the floor, connecting the subfloor space with each of said vertical passages. The space below the floor plate is divided into a series of longitudinally extending ducts or air passages, formed by means of vertical partition walls 54 extending between the bottom surface of the space 55 and the floor plate. The partition walls are arranged so as to form pairs of ducts adapted to supply air to each compartment through the vertical side passages thereof, and in the following manner.

The outer pairs of ducts 55, 55 extend only throughout the length of the first or outermost compartment 31, the inner end thereof being closed by providing the partition wall thereof with curved end portions, which terminate at right angles to the longitudinal portions of the walls and in abutting relation with the side wall of the space below the floor. The ducts 55, 55 communicate with the lower ends of the vertical passages 49, 49, associated with the compartment 31 through the openings 53, 53 at the lower ends of the vertical passages.

In like manner the pair of ducts 56, 56, located adjacent the outer pair of ducts 55, 55, communicate with the vertical passages of the middle compartment 32, the partition walls 54, 54 thereof extending rearwardly and terminating in curved end portions, which close the end of the duct, as before described. The ducts 56, 56 communicate with the lower ends of the vertical passages 50, 50 through the openings 53 at the lower ends thereof. The central or larger duct 57, formed between the inner walls 54, 54, communicates with the remaining portion of the space located below the rearmost compartment 33, said space in turn communicating with the vertical passages 51, 51 of said compartment 33 in the same manner as do 100 the ducts 55 and 56, heretofore described, namely, by openings similar to 53 at the lower ends of said vertical passages.

The outer or forward ends of the ducts 55, 56, and 57 communicate with a space or cross passage 58, common to all, extending transversely of said ducts and adapted to supply air to all of said ducts from a single source of supply, preferably a single passage 59, in which is mounted a fan or 105 blower 60, operated by a motor 61, both fan and motor being preferably mounted in the passage 59, which receives a supply of air through a suitable opening covered with a grating 62 set in the floor in front of the 110 furnace, the air thus forced into the several ducts being carried into the vertical passages and thence into the compartments from the sides thereof.

A preferable operating mechanism for ac- 115

tuating the deflecting plates, in a manner to move them laterally from the margins of the fixed deflecting plate and for the purpose hereinafter set forth, consists of parts as follows: Referring first to members of the operating mechanism, common to all of the plates 44, there is pivotally connected to each plate, adjacent to the lower margins of the upper plates 45 and intermediate 10 their lateral edges, links 65, preferably joined to journal bearing members 66 fixed to the plates. The links extend inwardly in a horizontal direction and are pivotally connected at their inner ends to links 67, 67 15 extending transversely of the links 65, said links 67, 67 being pivotally mounted upon the transverse plates 41 by means of bearing members 68, 68, fixed to said plates and having connection with the ends of the links 20 65 by means of downwardly depending connecting members 69, 69.

The links 67, 67, associated with each pair of plates 44, 44, are connected to each other by means of a transverse bar 70 and 25 short intermediate links 71, 71, pivotally connected at their ends to the ends of the bar 70 and the links 67, 67 intermediate the ends of the latter. Extending longitudinally of the air space below the grate and 30 centrally thereof is an endwise movable rod 72 mounted in bearings 73, preferably secured in apertures formed in the several plates 41 below the grate, said rod having rigid connection with each of the several 35 bars 70, the latter being provided intermediate their ends with collars, which surround the rod and are rigidly fixed thereto.

The rod 72 extends beyond the forward compartment, and is operated by a lever 74 40 mounted on and connected to the rod in the following manner: Extending transversely of the forwardly extending frame members 25, 25, is a shaft 75, rotatively mounted in bearings provided in said frame members, said 45 shaft projecting beyond the frame members on one side of the furnace. Intermediate the ends of the said shaft is provided a fixed crank arm 76, having connection with the end of said rod 72 by means of a link 77. 50 At the outer end of the shaft 75 is fixed the lever 74, adapted to be operated by hand to rotate the shaft 75 and, through the crank and link connection, to move the rod 72 endwise, the endwise movement of the rod 55 transmitting the desired swinging movement to the dampers through the intermediate arrangement of the bars 70 and links 71, 67, and 65.

From the foregoing description of the 60 furnace construction, the arrangement of deflecting plates coat in the following manner to accomplish the desired results. With the plates in vertical position and in contact with the margins of the fixed deflecting 65 plate of each compartment, there is formed

along the sides of the compartment two V-shaped troughs formed by the inclined surfaces of the fixed plate and the portions of the vertical plates extending above the edges of said fixed plate. The droppage, 71 upon striking the inclined surfaces of the fixed plate, is carried by gravity to either margin thereof and is retained and collected in the trough-like receptacle. Now, if it is desired to empty the troughs of the accumulation of droppage, the vertical plates are swung outwardly, by means of the operating mechanism, toward the side frame members, thereby permitting the accumulation of droppage to fall downwardly 80 through the opening thus formed. In the swinging movement of the plates, the upper member thereof preferably retains a vertical position, whereas the lower member assumes an inclined position over the opening to the forced draft ducts, thus the droppage in falling is directed or deflected, by the vertical and inclined surfaces, inwardly and onto the floor of the furnace, beneath the grate. In this manner, the forced 90 draft ducts are maintained free from accumulation of the droppage, and, furthermore, the droppage is discharged onto the floor where it can be readily removed and reclaimed by suitable tools. 95

The details of construction whereby the desired results are accomplished can obviously be modified without departing from the spirit of the invention, and for that reason I do not wish to limit the scope of 100 the invention, except in so far as specifically pointed out in the appended claims.

I claim as my invention:

1. In a furnace, the combination of a 105 grate, a deflecting plate mounted beneath said grate and inclined downwardly toward the edge of said grate, a movable plate extending transversely of said deflecting plate above and below the same, and adapted to be moved into and out of contact with the 110 margin of said deflecting plate.

2. In a furnace, the combination of a 115 grate, an inclined deflecting plate mounted beneath said grate, a movable plate extending transversely of and above and below the lower edge of said deflecting plate, and adapted to be moved into and out of contact with said edge of the deflecting plate, said movable plate being adapted to provide an inclined surface beneath the opening formed 120 by the movement of the same out of contact with said deflecting plate.

3. In a furnace, the combination of a 125 grate, a deflecting plate below said grate and inclined downwardly toward the side of the furnace, a movable deflecting plate pivotally mounted below said inclined plate and extending above the lower margin of and in contact with said inclined plate to form a trough, and means for swinging said 130

movable plate in a direction away from said inclined plate, to permit the contents of the trough to be discharged by gravity.

4. In a furnace, the combination of a grate, a fixed deflecting plate mounted in the air space below the grate, an air duct communicating with said air space below said deflecting plate, a movable deflecting plate mounted in said air space and normally extending above and in contact with an edge of said fixed plate, to form a trough, and means for swinging said movable plate away from said fixed plate and into a position to extend over the opening of said air duct.
5. In a furnace, the combination of a grate, an inclined deflecting plate mounted below said grate, the lower margin thereof terminating below a margin of said grate,

an air duct communicating with the air space below said grate through an opening in the floor of the furnace in substantially vertical alinement with the margin of said plate, a vertical deflecting plate pivotally mounted below said margin of the inclined plate and normally in contact with said margin and forming a trough, and means for swinging said vertical plate away from said inclined plate and over said opening of the air duct.

In testimony that I claim the foregoing as my invention, I affix my signature in the presence of two witnesses, this 2nd day of December, A. D. 1916.

HERMAN A. POPPENHUSEN.
